UNITED STATES PATENT OFFICE.

MATT ROY THOMPSON, OF OLYMPIA, WASHINGTON.

SLEEPING-HARNESS FOR INFANTS.

SPECIFICATION forming part of Letters Patent No. 613,334, dated November 1, 1898.

Application filed February 24, 1898. Serial No. 671,447. (No model.)

To all whom it may concern:

Be it known that I, MATT ROY THOMPSON, a citizen of the United States, residing at Olympia, in the county of Thurston and State 5 of Washington, have invented certain new and useful Improvements in Sleeping-Harness for Infants, of which the following is a specification.

My invention relates to a harness adapted 10 to be fitted to an infant to hold the same in bed and underneath the bed-clothing; and in such connection it relates to the construction and arrangement of such a device for the said purpose.

15 The principal objects of my invention are, first, to provide a simple, durable, and effective device or harness for application to a child or infant, so as to hold the same in bed and underneath the bed-clothing, and, second, 20 to provide a device of the character described applied as a harness to a child or infant and provided with movable front and back pieces slideable on cross-straps of the harness, so that the back piece may be detachably fastened 25 to a mattress or other portion of the bedding and the front piece be detachably fastened to the bedding, and while so fastened the child or infant, by reason of the construction and arrangement of the harness in application, may 30 be enabled to freely turn from one side to the other without the harness binding, giving any discomfiture to, or interfering in any manner with the rest of such person.

My invention, stated in general terms, 35 consists of a sleeping-harness for infants or children when constructed and arranged in the manner hereinafter described and claimed.

The nature and scope of my invention will be more fully understood from the following 40 description, taken in connection with the accompanying drawing, illustrating in perspective a harness embodying the features of my invention.

Referring to the drawing, *a* and *a'* represent 45 the right and left shoulder-straps, each of which at one end is formed into a double slip-loop *a²*, connected with the main body of the strap by a buckle *a³*, and the other end of each shoulder-strap is provided with a

50 snap-hook *b*, adapted to detachably engage rings *c* and *c'*, engaging the slip-loops *a²* of the respective shoulder-straps *a* and *a'*.

d and *d'* are front and rear cross-straps. The back strap *d* is fastened, by sewing or otherwise, to the body portions of the respective shoulder-straps *a* and *a'*, for example, as illustrated, while the front strap *d'* is fastened at the respective ends to the rings *c* and *c'*, connected with the shoulder-straps *a* and *a'*, and is provided with a buckle *e*, so as to 60 readily adjust the same to the child's chest or stomach without binding in position thereat. To the cross-straps *d* and *d'* are mounted, so as to freely move back and forth thereon, slip-pieces *f* and *f'*, provided at the respective 65 free ends with safety-pins or similar devices *g* and *g'*, whereby when the harness *A* in its entirety is secured to the infant over the shoulders and back and front of the person, as will be readily understood from the fore- 70 going description and illustration, the front and back slideable pieces *f* and *f'* may respectively be fastened to a mattress or other article of bedding and to the bed-clothing and in such manner as to permit the child to 75 readily turn about in the bed without discomfiture or harm to the child's body by reason of the use of such harness about the body of such person.

It will be observed from the drawing that 80 the shoulder-straps *a* and *a'* are adjustable, as well as the front cross-strap *d'*, so that the harness is adapted to infants of any size of body.

Having thus described the nature and objects of my invention, what I claim as new, and desire to secure by Letters Patent, is—

1. A device of the character described, consisting of two vertically-adjustable shoulder-straps, front and back cross-straps connecting said shoulder-straps with each other and one of which is adjustable, pieces of cloth or other material loosely mounted on said cross-straps, and said pieces of cloth or other material on said cross-straps provided with fastening means at the ends thereof, substantially as and for the purposes described. 95

2. A device of the character described, con-

sisting of two vertically-adjustable and separable shoulder-straps, front and back cross-
straps connecting said shoulder-straps with
each other, pieces of cloth or other material
5 connected with said cross-straps, one of which
is adjustable transversely, and said pieces of
cloth or other material mounted on said cross-
straps provided with fastening means and
adapted to be freely slid upon said cross-

straps, substantially as and for the purposes so
described.

In testimony whereof I have hereunto set
my signature in the presence of two sub-
scribing witnesses.

MATT ROY THOMPSON.
